Primary Examiner — Ricky Pham(74) *Attorney, Agent, or Firm* — Neal Gerber & Eisenberg LLP(57) **CLAIM**

The ornamental design for the cutting board, as shown and described.

DESCRIPTION

FIG. 1 is a perspective view of the cutting board according to the present invention;

FIG. 2 is a first side elevational view thereof;

FIG. 3 is a second side elevational view thereof; opposite from the first side shown in FIG. 2;

FIG. 4 is a third side elevational view thereof;

FIG. 5 is a fourth side elevational view thereof; opposite from the third side shown in FIG. 4;

FIG. 6 is a top plan view thereof; and,

FIG. 7 is a bottom plan view thereof.

The broken lines in the drawings illustrate the portions of the design that form no part of the claim.
